COIN COUNTER

Jerry C. Koci, Barrington, Ill., assignor, by mesne assignments, to Bert J. Payne Universal Control System, Inc., Joplin, Mo., a corporation

Filed May 16, 1958, Ser. No. 50,925

Term of patent 7 years

(Cl. D52—4)

Fig. 1 is a perspective view of a coin counter showing my new design;

Fig. 2 is a top plan view thereof;

Fig. 3 is a rear elevational view.

The undisclosed side of the coin counter is substantially the same in appearance as the side shown.

I claim:

The ornamental design for a coin counter, as shown and described.
